UNITED STATES PATENT OFFICE.

FRANK A. BREEZE, OF NEWBURGH, ONTARIO, CANADA.

MACHINE FOR MAKING PLOW-POINT MOLDS.

1,167,675.

Specification of Letters Patent. Patented Jan. 11, 1916.

Application filed June 3, 1915. Serial No. 31,928.

To all whom it may concern:

Be it known that I, FRANK A. BREEZE, a subject of the King of Great Britain, residing at Newburgh, in the Province of Ontario and Dominion of Canada, have invented certain new and useful Improvements in Machines for Making Plow-Point Molds; and I do declare the following to be a full, clear, and exact description of the invention, such as will enable others skilled in the art to which it appertains to make and use the same.

My invention relates to machines for forming sand molds for the casting of plow points and has for its object to provide a simple, durable and efficient construction whereby the pattern may be removed from the body of sand without mutilating the walls of the depression pattern in such sand. In accomplishing this result, I provide certain novel features of construction and unique combinations of parts hereinafter fully described and claimed, one embodiment of the invention being shown in the accompanying drawings wherein like reference characters designate corresponding parts throughout the several views and wherein:

Figure 1 is a top plan view of a machine constructed in accordance with my invention; Fig. 2 is a bottom plan view thereof; Fig. 3 is a vertical longitudinal section as seen along the plane indicated by the line 3—3 of Fig. 2, with all parts of the machine disposed to active position and illustrating the sand packed in the mold box; Fig. 4 is a similar view showing the two movable sections of the pattern swung downwardly without disturbing the cavity formed thereby in the sand; Fig. 5 is a vertical transverse section as seen along the plane indicated by the line 5—5 of Fig. 2, with the parts disposed as shown in Fig. 3; Fig. 6 is a view similar to Fig. 5 and showing the aforesaid parts in the positions disclosed in Fig. 4.

In these drawings which constitute a part of the application, the numeral 1 designates a horizontally disposed table having in its upper side a recess 2 from which a suitably shaped opening 3 leads to the under side of

said table as clearly disclosed in the several sectional views. The opening 3 snugly receives therein the plow point pattern 4 which is formed of a main body section 5 and a supplemental side section 6 received by an offset 7 formed in said body section.

The section 5 is of substantially triangular formation and is shaped upon its upper side in such a manner as to impart the necessary shape to one side of the sand mold 8 which is formed thereby, while the section 6 is constituted by an upright plate received by the offset 7 as hereinbefore stated, this offset being shown in the present application as formed in the edge of the body 5 corresponding to the land side of the point to be cast in the completed mold.

The section 5 is secured to the upper ends of a pair of L-shaped arms 9 disposed beneath the table, and fulcrumed at their opposite ends to a horizontally disposed shaft 10, this shaft being supported by appropriate brackets or bearings 11 which depend from the table. It is to be observed, that the section 5 is disposed longitudinally of the table 1 and that the arms 9 are positioned transversely thereof, but not at right-angles to the land side of said section 5, this being necessary in allowing certain projections with which the upper side of this section is provided, to be withdrawn from the sand mold 8 without injuring the cavity formed therein.

The upright plate or section 6, as clearly shown in the top and bottom plan views as well as in longitudinal sectional views, is disposed longitudinally of the table and is secured at its lower edge to a longitudinally extending arm 12 located beneath said table and fulcrumed to a bracket 13 depending therefrom, this arm 12 being shown in the present embodiment of the invention as disposed above the L-shaped arms 9. Thus it will be seen that when the arm 12 and the arms 9 are allowed to swing downwardly successively, the section 6 will be first withdrawn from the mold by practically a true downward movement, whereas the section 5 will not move directly downward but due to the angular arms 9, will swing laterally

and downwardly, thus causing it to leave the walls of the cavity in the mold with which it contacts, without sliding thereon to any appreciable extent. This positively overcomes any danger of mutilating the completed mold, provided the sand be packed therein to the necessary extent.

In order to maintain the two sections 5 and 6 of the pattern 4 in their uppermost active positions, and to lower the same successively as above suggested, any preferred means may be provided, this means being shown in the present application in the form of a cam shaft 14 rotatably mounted in bearings depending from the table 1, said shaft being disposed transversely of the table beneath the shaft 10 and the arm 12 as clearly shown in the several figures of the drawings. The shaft 14 is provided with a substantially circular cam 15 having one of its sides removed as at 15^a, and with a cam arm 16, the latter being normally disposed in contact with the under side of the arm 12 while the former supports thereon a post or the like 17 depending from the section 5 of the pattern 4. The relation of the cam 15 and the cam arm 16 is such as to cause the latter to release the arm 12 before the post 17 is released, it being therefore evident that the section 6 of the pattern 4 will be lowered ahead of the section 5 as hereinbefore suggested. Needless to say, in order to actuate the aforesaid cams, it is necessary to rotate the shaft 14, for which purpose any desired means may be provided, such means being incorporated in the present application in the form of a hand wheel 18.

In applying the invention to use, a mold box 19 is disposed around the cavity 2 and 40 is held in this position by studs 20 which rise from the table 1 through brackets 21 carried by said box. The two sections of the pattern 4 are now disposed to active position by proper manipulation of the hand wheel 18, and finally damp sand is packed in the box 19, it being thus evident that the sections 5 and 6 will form a cavity of the desired shape in the lower side of the body of sand, such cavity constituting the complete sand mold above mentioned. The pattern 4 may now be lowered by rotation of the hand wheel 18, during which operation the several walls of the cavity formed in the sand will remain undisturbed due to the fact that the 50 two sections 5 and 6 move in such directions as to prevent excessive sliding upon such walls. This result cannot be effectively accomplished by pattern sections movable in truly vertical planes as has been proven by 60 years of experimenting, it being thus evident that it is highly essential to mount such sections of the mold upon pivoted arms. Furthermore, in most cases, it is desirable to dispose these arms in such a manner as to cause 65 the same to swing in intersecting planes.

After the sand mold has been completed in the manner above set forth, the box with the mold therein is removed from the machine and the usual templet-plate (not shown) is disposed over the cavity in said mold. After this operation, the molten metal of which the point is to be formed, is poured into the aforesaid cavity through one or more runways formed by projections 22, such projections being disposed upon the top of the table 1 adjacent the edge of the recess or cavity 2. When the point is cast and the metal has cooled and hardened, the sand mold is broken as usual and the complete point is removed from the templet-plate.

From the foregoing description, taken in connection with the accompanying drawings, it will be evident that although comparatively simple construction has been provided for carrying out the object of the invention, the machine will be highly efficient in operation and will possess a number of advantageous features. Particular emphasis is laid upon the provision of the pivotally supported arms upon which the sections of the pattern are mounted, and upon the fact that these arms swing in intersecting planes, these features being deemed the most salient of the invention.

In the drawings, I have shown certain specific details of construction for producing probably the best results, and in the preceding, such details have been described, but it will be evident that I need not be limited thereto, otherwise than to the extent to which the appended claims restrict me.

I claim:—

1. A mold forming machine comprising a table having therein an opening, a pair of vertically movable pattern sections normally disposed in and closing said opening, and independent pivotally supported arms for the two sections swinging in intersecting planes.

2. A mold forming machine comprising a table having therein an opening, a pair of vertically movable pattern sections normally disposed in and closing said opening, independent pivotally supported arms swinging in intersecting planes and secured respectively to the two sections, and independent successively released supporting members retaining the two sections of the pattern in their raised active positions.

3. In a mold forming machine, the combination with a table having therein an opening, and a pair of downwardly movable pattern sections normally closing said opening, of a horizontal rock shaft below the table, a radial arm carried by said shaft for supporting one of said pattern sections until the shaft is rocked, and an eccentric on the edge of which the other section is supported until said shaft is rocked, said eccentric

having a portion of its edge disposed concentric with the shaft, whereby the pattern section supported by said eccentric will remain supported a predetermined length of 5 time after the other section has been released by its supporting arm.

In testimony whereof I have hereunto set

my hand in presence of two subscribing witnesses.

FRANK A. BREEZE.
